FLUORESCENT LAMP FIXTURE

Simon Gross, 2890 Coacoochee St., Miami, Fla.

Filed May 29, 1959, Ser. No. 56,142

Term of patent 14 years

(Cl. D48—23)

Fig. 1.

Fig. 2.

Fig. 3.

Fig.4.

Fig.5.

FIGURE 1 is a bottom perspective view of a fluorescent lamp fixture, showing my new design.

FIGURE 2 is a top perspective view thereof.

FIGURE 3 is an end elevational view thereof.

FIG. 4 is a side elevation thereof.

FIG. 5 is a sectional view thereof, taken on line 5—5 of FIG. 2.

I claim:

The ornamental design for fluorescent lamp fixture, as shown.
